DESIGN FOR A LADY'S HANDBAG OR SIMILAR ARTICLE

Julius Ballenzweig, New York, N. Y.

Application April 9, 1937, Serial No. 68,647

Term of patent 3½ years

To all whom it may concern:

Be it known that I, Julius Ballenzweig, a citizen of the United States of America, residing at #700 East 139th Street, in the Borough of Bronx, city and State of New York, having invented a new, original, and ornamental Design for a Lady's Handbag or Similar Article, of which the following is a specification, reference being had to the accompanying drawing, forming a part thereof, wherein the figure is a perspective view of a lady's handbag showing my new design. The other side of the bag is substantially plain.

I claim:

The ornamental design for a lady's handbag or similar article, substantially as shown and described.

JULIUS BALLENZWEIG.
